CLAIM

The ornamental design of a hat insert, as shown and described.

DESCRIPTION

FIG. 1 illustrates a top/front perspective view of a hat insert, according to an embodiment of the present disclosure.

FIG. 2 illustrates a top/rear perspective view of a hat insert, according to an embodiment of the present disclosure.

FIG. 3 illustrates a front elevation view of a hat insert, according to an embodiment of the present disclosure.

FIG. 4 illustrates a rear elevation view of a hat insert, according to an embodiment of the present disclosure.

FIG. 5 illustrates a left side elevation view of a hat insert, according to an embodiment of the present disclosure.

FIG. 6 illustrates a right side elevation view of a hat insert, according to an embodiment of the present disclosure.

FIG. 7 illustrates a top plan view of a hat insert, according to an embodiment of the present disclosure; and,

FIG. 8 illustrates a bottom plan view of a hat insert, according to an embodiment of the present disclosure.

The broken lines which define the bounds of the claimed design form no part thereof.
